UNITED STATES PATENT OFFICE.

MARTIN BARRI, OF CAMBRIDGE, MASSACHUSETTS, ASSIGNOR, BY MESNE ASSIGNMENTS, TO THE METEOR DESPATCH COMPANY, OF PORTLAND, MAINE.

PNEUMATIC CASH-CARRIER APPARATUS.

SPECIFICATION forming part of Letters Patent No. 395,203, dated December 25, 1888.

Application filed October 15, 1887. Serial No. 252,481. (No model.)

To all whom it may concern:

Be it known that I, MARTIN BARRI, of Cambridge, in the county of Middlesex and State of Massachusetts, have invented certain new and useful Improvements in Pneumatic Cash-Carrier Apparatus, of which the following is a full, clear, and exact description.

This invention consists, in combination with a pneumatic tube for the transmission therethrough of a carrier or other article provided with an opening at which the carrier or other article is inserted for transmission through the tube, and a door or cover to said opening constructed and arranged to be locked or fastened when closed, of means connected to said fastening device, constructed and arranged to be operated by the carrier or other article to unfasten or disengage said fastening device when the carrier or other article arrives at some desired point at or near the delivery end of the pneumatic tube or is delivered at said end of the pneumatic tube, all substantially as hereinafter fully described.

25 The invention also consists in the combination, with the pneumatic tube and its door or cover to said opening, of certain other parts constructed and arranged for operation substantially as hereinafter fully described, reference being had to the accompanying sheet of drawings, in which—

Figure 1 represents in front view a pneumatic tube arranged for the transmission of a carrier or other article therethrough from either end of the tube and having the present improvements applied thereto. Fig. 2 is a central vertical section of the end of the pneumatic tube at the right in Fig. 1; Fig. 3, a side elevation of the end of the pneumatic tube at 35 the left in Fig. 1; Fig. 4, a central vertical section of the tube on line 4 4, Fig. 1, but showing some parts in different positions; Fig. 5, a detail cross-section on line 5 5, Fig. 1, at the right, and Fig. 6, a detail cross-section on line 6 6, Fig. 1, turned a quarter round to the left.

In the drawings, A represents a pneumatic tube for the transmission therethrough of a carrier or other article from one end or station, B, to the other end or station, C, or vice

versa, the tube being properly secured to the table or stand D at each station and extending from one end to the other through the flooring E, as shown in Fig. 1.

F is an opening at the end B in the tube A, 55 where the carrier or other article is inserted into or delivered from the pneumatic tube at such end, and G is another and similar opening in the tube A at the end C for the same purposes. These openings F and G are made 60 by cutting out a portion of the front side of the tube, as shown, sufficiently large to admit and deliver the carrier or other article to be transmitted through the tube, and at the opening F is a cover or door, H, made of a 65 short piece of tubing closely encircling but free enough to move up and down over the tube A, and when down to close and when up to open its opening F, it being limited in each movement by abutments or shoulders a a, respectively, on the tube. On each side of this door or cover H is a spiral spring, J, secured to it and to the sides of the tube A, which by their tension act to hold the cover or door H up in the position shown in Figs. 3 and 4 and 70 in Fig. 1 at the left, and when the cover is moved down over and to close its opening in the tube, as shown in Fig. 2 and the right end of Fig. 1, it is against its springs J, which, when the door or cover is free, return it to its 75 position to leave its opening free and clear.

At the opening G at the station end C is a door or cover, H, having springs J and abutments constructed and arranged for operation at such opening the same as at the opening F.

The tube A below the table, at each end, as at K, is enlarged in order to allow for a short piece of tubing, L, to closely fit within the tube A, and yet be free to move up and down 90 therein within certain limits, and this tube or pipe L has an opening, R, in one side, which, when the tube is down in the position shown in Fig. 2, comes opposite to and is coincident with an opening, Q, to a pipe, S, which connects and communicates with the air-motor, and when it is moved up its part b is opposite to and over the opening Q, as shown in Fig. 4, closing the same, the tube serving as a valve or gate to said pipe S. Its internal diameter 95 100

- is the same as the internal diameter of the main part of the pneumatic tube, so that the carrier or other article can pass through it freely.
- 5 Each tube or valve is connected by pitman-rods d to the cover or door H on the outside of the pneumatic tube by pins or screws f, g , the ones g to the valve or gate L passing through vertical slots h in the tube A .
- 10 When a cover, H , is moved down to close the opening F , it carries with it the valve or gate L , moving it into position for its opening R to be opposite to the opening Q , leading to the pipe S , as shown in Fig. 2. Thus
- 15 when a carrier or other article is to be transmitted through the tube A it is put in the tube at one of the openings, F or G . Its cover H is then moved down over its opening, which correspondingly moves the gate or valve L
- 20 down for its opening R to be coincident with the opening Q , leading to the pipe S , when, if air is forced through the pipe S , it will pass to the tube A through the openings Q, R , forcing the carrier or other article along the
- 25 tube A to the other end, where it will be delivered, when, the door or cover at the end from which the carrier has been transmitted being allowed to rise to open its opening, its valve L will move with it and correspondingly close the opening to the pipe S and shut the air off from the motor. The pneumatic tube at each end extends up a short distance above the opening and cover, as shown, being closed by any suitable cap or head, M , and
- 30 above each opening F or G in the tube is a piston-head, N , arranged to slide up and down freely therein. A central stem, m , extends up from the piston-head N and projects through a central vertical opening, n , in a block, p , secured within the tube A , and by a vertical longitudinal slot, q , engages with one end of a lever, T , passing through a slot, r , in the tube and pivoted at its other end at t to an arm, U , secured to the outside of the tube.
- 35 Connected to this lever T at u is a wire, v , which runs down the side of the tube A and through the floor E and connects to one arm of a bell-crank, W , pivoted below the floor, the other arm of this bell-crank being connected by a wire, Y , to an arm of another bell-crank, Z , pivoted below the floor at the end of the tube, which bell-crank by its other arm is connected by a wire, A' , to an arm of a lever, B' , pivoted at v to a suitable support, its other arm having a notch, w , which is in position to engage with a notch, y , in an extension of one, a' , of the pitman-rods d when the cover is moved down into position to close its opening, as shown in Fig. 1 at the station
- 40 C and in Fig. 2. This lever B' has a spiral spring, b' , secured to it and to the support d' , the tension of which serves to keep the catch-lever B' to its engagement with the catch of the cover or door and to force it to engage therewith when the door is moved down to close its opening.

With the apparatus in its position shown

in Fig. 1, which is represented as just having had a carrier or other article inserted at the opening G at the station C , and the cover or door at such end moved down to close said opening (it having a handle, E' , for convenience in operating it) and locked in such position by the spring-catch B' , and the valve or gate L as down in position for air to pass to the pneumatic tube

75 through its pipe from the air-motor, the air-motor being in operation, the carrier is forced along the tube A below the floor to the left and up and delivered at the end or station B .

When the carrier or other article arrives at

80 the station B , it is carried by its momentum past the opening F at such station, and up to and striking against the piston-head N , forces

85 and raises it, and by its stem m the lever T , (see Fig. 4,) which pulls by the wires and bell-crank connected therewith upon the lever B' , at station C , moving it and disengaging its catch w from the catch-rod a' of the cover or door, which then being free to move, its springs

90 J exert their power and raise it, uncovering its opening in the pneumatic tube ready for

the insertion or delivery of a carrier therat. After the carrier strikes the piston-head N it

95 falls therefrom and out at the opening F at such end of the tube and is delivered onto

100 the table. Back of each opening F or G is a wire spring, C' , secured at d' within a casing,

105 D' , at the side of the tube and projecting by its central bulging portion, f' , into the pneumatic tube, as shown in Fig. 4, in the line of

110 travel of the carrier through the tube, and its purpose is, as the carrier falls back from the piston-head N , for it to force the carrier by

115 its tension out at the opening F or G to insure its discharge at such opening and not

120 fall back down in the tube A below it. The

125 spring, however, is arranged to act lightly, so as to have practically no effect on the carrier when it passes by it in coming from the transmitting end of the tube, the momentum

130 of the carrier at such time being sufficient to insure that it shall pass to and strike the piston-head N to disengage the catch w from the

135 door or cover at the end from which the carrier was transmitted; but as the momentum

140 of the carrier when it falls from the piston-head is reduced greatly and is quite light the

145 spring is of sufficient power to act upon the carrier to then throw or force it out at the

150 opening, where it will fall upon the table

155 lightly. This spring being the subject of my application Serial No. 251,631, no claim is

made to it in this application.

When the air-motor is operated by an engine or in any way independent of the person

125 sending the article through the tube in transmitting any article through the pneumatic tube, he has only to insert it therein and close

130 the door, which locks itself, when he can leave the apparatus and attend to other du-

ties, for the carrier when it arrives at the de-

135 liveries end of the tube will unlock and re-

lease the door, as described, which, with its

valve, is then raised by its springs, leaving

its respective opening in the tube free for the insertion or delivery of a carrier thereat and shutting off the air from the air-motor.

In lieu of using bell-crank for changing the direction of pull of the wires, the wires can be adapted to run over pulleys, or the portion of the wire at such places can be of chain form instead.

The valve L is connected to the door at its end of the tube in such manner that it will not be moved to open until the door is nearly closed to prevent as much as possible air passing out at the opening F or G when shutting the door after placing a carrier therein, and this is accomplished by having a longitudinal slot, g', in each pitman-rod d, as shown in Figs. 2 and 3 more particularly, by which, when the door is nearly closed, the upper end, h', of the slots g' will abut against the pins g of the valve, and then in the continued downward movement of the door will move the valve down and uncover the opening Q of the pipe S, leading to the air-motor for the air to pass therefrom to the pneumatic tube, the movement of the door being so much in excess of the required movement of the valve that it enables the closing of the valve to be done as described.

Having thus described my invention, what I claim is—

1. The combination, with a pneumatic tube provided with an opening for the insertion of a carrier or other article, and a cover or door adapted to move down and over said opening to close it, of a spring-catch arranged and adapted to engage with said door and hold it so closed, and connected to mechanism for operation thereof by the carrier or other article in its passage through the tube to release or disengage said catch, for the purpose specified.

2. The combination, with a pneumatic tube provided with an opening for the insertion of a carrier or other article, and a cover or door adapted to move down and over said opening to close it, of a spring-catch arranged and adapted to engage with said door and hold it so closed, and connected to a piston-head arranged to move back and forth in said tube for operation thereof by the carrier or other article in its passage through the tube to release or disengage said catch, for the purpose specified.

3. The combination, with a pneumatic tube

provided with an opening for the insertion of a carrier or other article, and a cover or door adapted to move down and over said opening to close it, of a spring-catch arranged and adapted to engage with said door and hold it so closed, and connected by wires and suitable bell-crank to a piston-head arranged to move back and forth in said tube for operation thereof by the carrier or other article in its passage through the tube to release or disengage said catch, for the purpose specified.

4. The combination, with a pneumatic tube provided with an opening, F, for the insertion of a carrier or other article, and an opening, Q, communicating with any suitable air-motor, and a cover or door to said opening F, connected to a gate or valve, L, of the opening Q, of a spring-catch arranged and adapted to engage with said door and hold it so closed, and connected to mechanism for operation thereof by the carrier or other article in its passage through the tube to release or disengage said catch, for the purpose specified.

5. The combination, with a pneumatic tube provided with an opening, F, for the insertion of a carrier or other article, and an opening, Q, communicating with any suitable air-motor, and a cover or door to said opening F, connected to a gate or valve, L, of the opening Q, of a spring-catch arranged and adapted to engage with said door and hold it so closed, and connected to a piston-head, P, arranged to move back and forth in said tube for operation thereof by the carrier or other article in its passage through the tube to release or disengage said catch, for the purpose specified.

6. The combination, with a pneumatic tube provided with an opening for the insertion of a carrier or other article, and a cover or door adapted to move down and over said opening to close it, of a gate or valve, L, to the opening Q between said tube and the air-motor, connected to said cover or door by pitman-rods d and pins g and having slots g', substantially as and for the purpose specified.

In testimony whereof I have hereunto set my hand in the presence of two subscribing witnesses.

MARTIN BARRI.
